(57) CLAIM

The ornamental design for a cigarette lighter clip, as shown and described.

DESCRIPTION

FIG. 1 is a perspective view of cigarette lighter clip showing my new design.

FIG. 2 is a front elevational view;

FIG. 3 is a rear elevational view;

FIG. 4 is a left side elevational view;

FIG. 5 is a right side elevational view.

FIG. 6 is a bottom plan view;

FIG. 7 is a top plan view; and,

FIG. 8 is another perspective view.

The broken lines are shown for illustrative purposes only and form no part of the claimed design.
